(57) **CLAIM**

The ornamental design for a bottle, substantially as shown and described.

DESCRIPTION

FIG. 1 is a front perspective view of a bottle in accordance with the present invention.

FIG. 2 is a back perspective view of the design thereof.

FIG. 3 is a front view of the design thereof.

FIG. 4 is a back view of the design thereof.

FIG. 5 is a right side view of the design thereof.

FIG. 6 is a left side view of the design thereof.

FIG. 7 is a top side view of the design thereof; and,

FIG. 8 is a bottom side view of the design thereof.

The broken lines shown in the drawings depict portions of the bottle that form no part of the claimed design.

1 Claim, 8 Drawing Sheets
